[57] CLAIM

The ornamental design for an environmental chamber
for stimulating plant growth, as shown and described.

DESCRIPTION

FIG. 1 is a front view of an environmental chamber for
stimulating plant growth showing my new design;

FIG. 2 is a rear view thereof;

FIG. 3 is a right side view thereof, the left side view
being substantially a mirror image thereof;

FIG. 4 is a top view thereof; and,

FIG. 5 is a bottom view thereof.

FIG. 1**FIG. 2*****FIG. 3*****FIG. 4****FIG. 5**
